[57] **CLAIM**

An ornamental design for a window shroud for a passenger van, as shown and described.

DESCRIPTION

FIG. 1 is a perspective view of a window shroud for a passenger van illustrating my new design;

FIG. 2 is a front side elevational view thereof;

FIG. 3 is a left end elevational view thereof;

FIG. 4 is a rear side elevational view thereof;

FIG. 5 is a right end elevational view thereof;

FIG. 6 is a bottom plan view thereof;

FIG. 7 is top plan view thereof; and,

FIG. 8 is a perspective view thereof, the dotted line showing of a vehicle is for illustrative purposes only and forms no part of the claimed design.
